Inventor:

Roger Braunstein

By Lawrence Langner
Attorney

UNITED STATES PATENT OFFICE.

ROGER BRAUNSTEIN, OF PARIS, FRANCE.

APPARATUS FOR EFFECTING THE GRIPPING, THE EXTRACTION, AND THE FOLDING OF SHEETS OF PAPER CONTAINED IN A MAGAZINE.

Application filed July 20, 1921. Serial No. 486,255.

(GRANTED UNDER THE PROVISIONS OF THE ACT OF MARCH 3, 1921, 41 STAT. L., 1313.)

To all whom it may concern:

Be it known that I, ROGER BRAUNSTEIN, a citizen of the French Republic, residing at Paris, 83 Bd. Exelmans, have invented Im-
5 provements in Apparatus for Effecting the Gripping, the Extraction, and the Folding of Sheets of Paper Contained in a Magazine (for which I have filed an application in France, July 16, 1920, Number 520,612),
10 of which the following is a description.

This invention has for its object to provide an apparatus enabling sheets of paper contained in a magazine to be gripped, extracted and folded in a simple and effective
15 manner.

In order to enable the invention to be understood, it will be described with reference to the accompanying drawing which illustrates by way of example the apparatus
20 according to the invention.

Figure 1, is a sectional elevation of the apparatus.

Figure 2, is a plan view partly in section.

The same reference numerals designate
25 the same parts in the two figures of the drawings.

The apparatus in question is adapted to act upon sheets of paper of any size, weight and consistency, but especially upon sheets
30 of thin paper, such as cigarette paper, which have been cut in advance in such a way as to present sheets of the desired width, and of a length which may be equal to the length
35 which it is desired to obtain, or some multiple of this latter.

The apparatus is applicable in particular to cases where it is required to feed sheets to roughened rolls disposed in a known manner and serving to crimp paper for
40 making up cigarettes, toilet sheets, for impressed prescriptions and so forth.

The apparatus consists essentially of two parallel cylinders 1 and 2 supported at each end by spindles 3 and 4 mounted in bearings
45 at 5 and 6; the bearings of one of the cylinders may be adjustable for example by means of micrometer screws in such a way as to enable the pressure of the cylinders one against the other to be increased or reduced as may be required. The cylinders are driven by means of suitable gearing 4',
4'', driving the spindle 4 for example and actuated from an engine shaft, while the two

cylinders are geared together by pinions 11 and 12 of equal size. 55

The exterior surface of the cylinders is smooth but is provided along one or more longitudinal strips with a gripping surface 7, 8, of a convenient width, adapted to effect by frictional action the gripping and the extraction of the sheets of paper, as will be described below. The cylinders in question may, for the rest, be covered with a suitable plastic covering material (leather, compressed paste-board, rubber and so forth) in the space comprised between two parallel lines in the neighbourhood of the gripping surfaces 7 and 8 referred to above, and in the parts at 9 and 10 of the cylinders which insure the formation of the fold. 60

The cylinders 1 and 2 are driven in the direction indicated by the arrows f^1 , f^2 , respectively by means of the gearing already described. 65

Above the cylinders is disposed a magazine 13 containing the sheets of paper which are to be extracted and folded. The bottom 14 of this magazine is placed at a short distance from the tangent plane common to the two cylinders 1 and 2. 70

The gripping surfaces of the cylinders during the rotation of these latter pass through an aperture at 15 in the bottom 14 of the magazine and they engage frictionally the sheet of paper at the bottom of the pile of 85 sheets P contained in the magazine. The bottom sheet seized in this way is caused to form a loop at the middle between the two cylinders, and this becomes converted into a fold or crease when the sheet passes 90 through the line of contact at 16 between the cylinders.

The folded sheet of paper subsequently becomes released by the cylinders as they continue their rotation, and falls in the direction indicated by the arrow p, into a receiving magazine or any suitable receptacle, according to the ultimate destination of the sheets of paper, (for example into the feeding aperture of the crimping rolls in the 100 case where the apparatus is applied to sheets of paper intended for automatic distribution as crimped sheets).

The apparatus constructed as described above operates without the necessity of employing an air exhausting machine and with- 105

out the comparatively complex and delicate devices which are necessary in other machines of this character for insuring the seizing and the extraction of the sheets by 5 the adherence of these sheets to the surface of the cylinders, such adherence being in those cases obtained solely by means of suction created in the interior of cylinders which are hollow and provided with rows of holes 10 along one or more longitudinal lines.

However, in order to insure regularity in the operation of the apparatus according to this invention, and to render it independent of the amount of paper contained in 15 the magazine, or of the greater or lesser degree of glazing of the surface of the paper, I may combine the action of engagement by means of suction through holes in the hollow cylinders.

20 In this case, the apparatus above described is combined with an apparatus similar to that set forth in the specification of my co-pending patent application of even date entitled "Improvements in apparatus for effecting the extraction successively of sheets 25 of paper contained in a magazine, and for folding such sheets." In that apparatus hollow cylinders are used with longitudinal perforations in rows thereon, and the cylinders 30 are connected through trunnions with a box adapted to be connected alternately to suction or opened to the atmosphere as the cylinders rotate.

Having now particularly described and ascertained the nature of my said invention 35 and in what manner the same is to be performed, I declare that what I claim is:

The combination with a magazine for holding sheets of thin paper in a pile and having an opening in its bottom, of means 40 for gripping said sheets one by one and extracting them through said opening and folding them, comprising two parallel cylinders 1, 2 arranged directly beneath said opening, said cylinders being provided in their surfaces with narrow strips 7, 8 of friction material extending longitudinally of said cylinders, said cylinders being further provided adjacent said strips 7, 8 with narrow strips 9, 10 of plastic material, said cylinders being 45 geared together in such manner that when they are driven with their upper surfaces turning toward each other, said strips 7, 8 will simultaneously frictionally engage through said opening the bottom surface of 50 the bottom sheet in said magazine and in extracting it through said opening give it a buckle which is then gripped by the plastic strips 9, 10 to complete the folding.

55 In testimony whereof, I have signed my name to this specification in the presence of two subscribing witnesses.

ROGER BRAUNSTEIN.
